UNITED STATES PATENT OFFICE.

REINHOLD HOPPE, OF EAST OAKLAND, CALIFORNIA.

SPRING ANKLE-SUPPORTER.

1,236,714.

Specification of Letters Patent. Patented Aug. 14, 1917.

Application filed April 4, 1917. Serial No. 159,608.

To all whom it may concern:

Be it known that I, REINHOLD HOPPE, a citizen of the United States, residing at East Oakland, in the State of California, have 5 invented certain new and useful Improvements in Spring Ankle-Supporters, of which the following is a specification, reference being had to the accompanying drawings, forming a part hereof.

This invention relates to a spring ankle supporter and is designed primarily with reference to its association with the uppers of shoes although as the description proceeds it will be evident that the supporter 10 may be incorporated to equal advantage in pliable ankle braces. It has been proposed to give the ankle some support by means of ribs or stays inserted in the uppers of shoes or in pliable ankle braces in such 15 manner as to provide a more or less flexible corset for the ankle to protect it from wrenches and strains, and it has also been proposed to place relatively stiff metal braces at the sides of the ankle to prevent it from 20 turning. The support given to the ankle by these known devices while helpful to a degree has been dependent for its efficacy upon the partial or complete incasing of the ankle in the corset or upon the bracing 25 of the ankle at the sides. The present invention has for its principal object to provide a spring supporter for ankles which is founded on a novel principle which insures greater effectiveness than known devices, is of simpler construction and more 30 inexpensive and gives the ankle absolute freedom without constriction while holding it firmly against turning in much the manner of a splint. In accordance with the invention a single spring metallic rib is secured along the rear of the shoe upper or 35 ankle brace, conforming readily to the natural curvature of the ankle by reason of its flexibility, but formed with such width 40 and stiffness transversely as to hold it against flexure in that direction so as to prevent the ankle from turning. The improved rib is held snugly against the rear side of the ankle by the pliable shoe upper 45 or ankle brace in much the manner of a splint, except that while the ankle is prevented from turning laterally by the stiff 50 splint its natural flexure forwardly and rearwardly is permitted freely. In the preferred embodiment of the invention, this 55 spring rib is provided with a flanged foot

which is secured to the heel of the shoe in such manner that the rib is held against lateral movement with relation to the shoe, so that any movement laterally of either the 60 upper or the heel is transmitted directly to the rib and vice versa, so that relative lateral movement between the ankle and the heel or sole of the shoe is prevented. Further details of the construction and a 65 recital of the advantages will appear herein-after in connection with the description of the accompanying drawings, in which—

Figure 1 is a fragmentary view of a shoe to the heel of which an improved spring 70 supporter is secured.

Fig. 2 is a detail view in transverse section taken along the line 2—2 of Fig. 1 and looking in the direction of the arrows.

Fig. 3 is a detail view in elevation of the 75 improved spring rib shown in Fig. 1.

Fig. 4 is a view similar generally to Fig. 1 but showing a different embodiment of the spring rib in which the flanged foot is 80 omitted.

It will appear as this description proceeds and especially in connection with the embodiment of the spring rib shown in Fig. 4 that the improved rib may be incorporated in a pliable ankle brace of usual construction and have to a great extent all of the advantages which flow from its use in a shoe. In such an ankle brace the principle of the invention will be fully retained, this principle being best likened, for an understanding, to a splint. It will be appreciated that where a bone is to be held against turning, a splint is a usual and natural way of holding it, but the difficulty of applying this splint principle to the support of an 85 ankle has presented special difficulties because of the need for free flexure of the ankle backward and forward during the natural movements thereof. The primary object of the invention is, then, to adapt the 90 principle of the splint to a spring ankle supporter, so that while the ankle will be securely held against turning in such ways as to cause sprains and wrenches, it is not unduly constricted as in the known corset 95 constructions and is permitted free flexure forward and backward to conform to the natural movements of the foot.

Referring now to Fig. 1, which illustrates so much of a shoe as is necessary for an understanding of the application of the improved spring supporter thereto and which

is not intended to show in any detail or with any degree of accuracy all of the constituent plies of a shoe structure, it will appear that the heel α to which is secured the pliable upper b is overlaid with an inner sole c and supports a counter d for the purpose of stiffening the shoe in a manner well known. The improved spring supporter e has its general form and characteristics illustrated in Figs. 2 and 3 from which it appears that the rib is curved somewhat in cross section to conform to the transverse curvature of the ankle at the rear and is also curved longitudinally to conform to the longitudinal curvature of the ankle. In this embodiment the rib e is flanged, as at e' , to provide a foot by means of which the rib may be secured fixedly to the heel α , as by means of studs f , the flange e' and these studs f being conveniently covered by the insole c . The rib e when thus secured in place is, of course, entirely hidden from view by the usual lining g and the upper b along the rear seam or by a tongue b' , which may overlie this rear seam of the upper. The physical properties of the spring supporter e are of the essence of the invention. The rib must be relatively stiff and yet springy. It must yield freely to conform to the flexing of the ankle forward and backward during the natural movements of the foot, and yet it must be of such width as to be absolutely stiff transversely and unyielding, so that lateral movements of the ankle will be entirely prevented. The upper b presses the rib e firmly against the rear of the ankle and thereby forms with it a support which may best be compared to a splint. By reason of the fixed relation of the rib e to the heel α by the studs f relative lateral movement between the heel and the rib and between the heel and the upper is entirely prevented. Lateral movement of the ankle with relation to the heel and sole of the shoe or with relation to the upper is absolutely prevented, since any such movement of the ankle is communicated in equal degree to the rib and to the sole and heel. On the other hand the natural movements of the foot, as during walking are not impeded.

In Fig. 4, the rib E has no flanged foot corresponding to the flange e' of the embodiment above described, although this rib is secured in the upper of the shoe along the rear seam thereof in exactly the same relation to the ankle as previously described. The rib may be secured conveniently to the counter d by means of studs f so that the same general effect is produced as in the other embodiment. The counter, as is known, is stiff and is secured fixedly to the

heel, so that any movements of the counter communicated to it through the rib E will be communicated to the heel α in the precise manner pointed out above. This rib has the same general properties as the other form of rib, so that while free flexure of the ankle is permitted, lateral movement thereof is prevented since the ankle is held in a splint-like grip.

As noted hereinbefore other embodiments of the invention may be employed to equal advantage. The gist of the invention resides in the provision of a single spring rib disposed along the rear of a shoe or ankle brace and held in such relation to the ankle as to partake of the functions of a splint in so far as is desirable to prevent the lateral movement of the ankle and yet permit free flexure of the ankle during natural movements of the foot.

I claim as my invention:

1. In a shoe in combination with the heel portion and upper, a spring metal ankle supporter secured to the upper along the rear thereof to lie along the rear of the ankle, and means to secure the supporter fixedly at its lower end to the heel portion, the supporter being formed to yield freely to the natural flexure of the ankle forwardly and rearwardly while stiff and unyielding transversely to hold the ankle against lateral turning as by a splint-like action.

2. In a shoe in combination with the heel portion and upper, a metallic spring rib secured to the upper along the rear thereof to lie along the rear of the ankle, a stiff flanged foot on the rib, and means to secure the foot fixedly to the heel portion, the supporter being formed to yield freely to the natural flexure of the ankle forwardly and rearwardly while stiff and unyielding transversely to hold the ankle against lateral turning as by a splint-like action.

3. In a shoe in combination with the heel portion and upper, a stiff flanged foot on the rib, studs to secure the foot to the heel portion, an insole overlying the foot and the studs, and a metallic spring rib secured to the upper along the rear thereof and curved in cross section to conform to the transverse curvature of the ankle and curved longitudinally to conform to the longitudinal curvature of the ankle, said rib being formed to yield freely to the natural flexure of the ankle forwardly and rearwardly while stiff and unyielding transversely to hold the ankle against lateral turning as by a splint-like action.

This specification signed this 31st day of March, A. D. 1917.

REINHOLD HOPPE.
